UNITED STATES PATENT OFFICE.

GEORGE DILLEY WATSON, OF PARKERSBURG, WEST VIRGINIA, ASSIGNOR OF ONE-FOURTH TO WILLIAM H. KESSELMAN, ONE-FOURTH TO LEWIS P. KESSELMAN, AND ONE-FOURTH TO CHARLES I. MASTERS, OF PARKERSBURG, WEST VIRGINIA.

TRAIN-SIGNAL.

No. 839,683.

Specification of Letters Patent

Patented Dec. 25, 1906.

Application filed May 29, 1906. Serial No. 319,278.

To all whom it may concern:

Be it known that I, GEORGE DILLEY WATSON, a citizen of the United States, and a resident of Parkersburg, in the county of Wood 5 and State of West Virginia, have invented a new and Improved Train-Signal, of which the following is a full, clear, and exact description.

This invention relates to train-signals.

10 The object of the invention is to produce apparatus of this character which will operate to prevent wrecks due to landslides or similar causes.

The invention consists in the construction 15 and combination of parts to be more fully described hereinafter and particularly set forth in the claims.

Reference is to be had to the accompanying 20 drawings, forming a part of this specification, in which similar characters of reference indicate corresponding parts in all the figures.

Figure 1 is a perspective showing a railway-cut and illustrating the manner in which the apparatus is constructed and operated. Fig. 2 is a side elevation of one of the signal-posts, certain parts being broken away. Fig. 3 is a front elevation of the signal-post shown in Fig. 2, certain parts being broken away. Fig. 4 is a cross-section taken on the line 4 4 25 30 35 40 45 50 55 60 65 70 75 80 85 90 95 100 of Fig. 3. Fig. 5 is a side elevation showing the arrangement of the apparatus adopted where the signal comprises an electric light. Fig. 6 is a perspective view illustrating the application of the invention to a tunnel. Fig. 7 is a cross-section illustrating the manner of applying the invention to prevent accidents from a lateral shifting of the track, and Fig. 8 is a plan showing its use to indicate the destruction of a bridge.

40 Referring more particularly to the parts, and especially to Fig. 1, the drawing represents a railway-cut on the sides of which high banks lie which endanger the track from landslides or boulders which may roll down in such a way as to cause a wreck.

45 In applying my invention I provide at suitable points signal-posts 1 and 2, and between these posts I set a plurality of intermediate posts or staves 3, and these support 50 horizontally-strung wires 4, so that a fence or guard 5 is formed adjacent to the track

and on the side where the danger from landslides is expected.

Referring now especially to Figs. 2 and 3, these wires 4 have their extremities attached 55 to bolts 6, which are slidably mounted in the posts 1 and 2. In the rear sides of the posts recesses are formed which receive thimbles 7, and in these thimbles helical springs 8 are mounted, respectively. These springs 8 60 thrust against collars 9, attached to the ends of the bolts, and the springs are of sufficient strength to maintain the wires 4 substantially taut. Throughout their length the wires 4 are supported upon the intermediate 65 posts 3 by means of rollers or pulleys 10.

Near its base each post is provided with a trip-lever 11, which is pivotally mounted upon a suitable bolt 12, as indicated. This lever lies adjacent to a recess 13, which is 70 formed longitudinally in the corner of the post, as indicated. The upper extremity of the lever affords means for controlling a semaphore 14, which is pivotally attached to the side face of the post at the point 15. The 75 butt-end of the semaphore is provided with a notch 16, and when the semaphore is in a vertical position, as indicated in Fig. 2, this notch 15 may be engaged by the tip of the lever 11. The bolts 6 pass through the lower 80 portion of the trip-lever 11 and on each side of the lever are provided with rigidly-attached collars 17. At a suitable point near the lower end of the semaphore when disposed in a vertical position, as shown in Fig. 85 2, I provide a spring-case 18, in which there is arranged a small helical spring 19. When the semaphore is in the set position (shown in Fig. 2,) the spring is compressed, so that when the trip-lever is operated to release the semaphore the spring throws the semaphore out of its central position. In this way the long 90 arm of the semaphore which constitutes the signal descends into a substantially horizontal position, as indicated in dotted lines in Fig. 2 and in full lines in Fig. 1.

From the arrangement described it will be understood that if a landslide should occur, as illustrated in Fig. 1, the movement of the earth or rocks will operate the wires 4 in such a way as to release the semaphore, which will then descend into the danger position.

In order to make the apparatus useful at night as well as in daytime, I provide the semaphore 14 with a red glass 20, and this glass is adapted to lie in front of a signal-lantern 21, mounted upon a suitable bracket 22. In this way the lantern will be transformed into a danger-signal. Where it is desired to use an electric light as a signal in connection with a semaphore, I provide an arrangement such as that indicated in Fig. 5. In this case I attach to the semaphore-post 23 a semaphore 24, which is actuated in the manner described above. I provide an electric signal-light 25, attached to the post in any suitable manner, which is in a circuit 26 with a suitable battery 27. On the under side of the semaphore-arm 24 I provide an insulating-block 28, carrying a contact 29. In a suitable position I attach to the post a bracket 30, carrying a pair of contacts 31, which are also included in the aforesaid circuit 26, the conductor from one contact running to the light, while the conductor from the other contact runs to the battery 27. When the semaphore is in its danger position, the contact 29 bridges the contacts 31, so that the circuit is closed through the lamp from the battery. In this way when the apparatus is operating at night an efficient danger-signal will be given.

The invention is applicable in preventing accidents from a cave-in at a tunnel. In Fig. 6 its application in this connection is illustrated. When used for this purpose, the guard-fence 32 is arranged at the side of the track and extended a sufficient distance to enable a fast-moving train to come to a stop between the semaphore-post 33 and the tunnel 34. The wires of the guard-fence 32, which pass to the roof of the mouth of the tunnel, are strung along the under side thereof. From this arrangement if a cave-in should occur the wires will be pulled or become broken, so that the signal 35 will be operated.

In Fig. 7 the device is shown applied to prevent an accident from the lateral shifting of the track. In this instance one of the rails, such as the rail 36, has an anchor-plate 37 secured to the same and to the cross-tie 39. To this anchor-plate a cable 38 is attached, which may pass under a guide-pulley 40, set up at the side of the tracks, as shown. The extremity of this cable 38 is attached to one of the wires of the guard-fence 41, preferably the bottom wire 42, as indicated. If desirable, in order to protect the cable 38 the same may be incased in a sheath or covering of wood or similar material.

In using the device to prevent an accident from the destruction of a bridge I adopt the arrangement shown in Fig. 8, wherein 43 represents the bridge across which the track

passes. On the side of the track a guard-fence 44 runs, and the wires of this fence pass 65 across the stream which runs under the bridge. At the side of the bridge adjacent to the fence 44 anchor-plates 45 are provided, similar to the anchor-plate 37, and these are connected by cables 46 with any of 70 the wires of the fence 44. Evidently if the bridge should be washed away or destroyed the cables 46 would operate the signal. It should be understood that the guard-fence 44 will be placed on the upstream side of the 75 bridge, so that if a washout occurs the cables 46 will be sure to operate the signal.

Special attention is called to the fact that the signal will be operated not only by a pull in the wires of the guard-fence, but also by a 80 rupture or breaking of these wires. In the latter instance the springs in connection with the wires at the signal-posts will operate when their tension is released to actuate the semaphore.

Having thus described my invention, I claim as new and desire to secure by Letters Patent—

1. In apparatus of the class described, in combination, a signal-post, a signal carried thereby, a trip-lever controlling said signal, and a plurality of wires extending longitudinally of the track and constituting a guard, said wires being connected with said trip-lever, means for attaching said wires in said 90 post, and springs respectively connected with said wires and maintaining the same taut. 95

2. In apparatus of the class described, in combination, a signal-post, a semaphore mounted thereupon, a trip-lever controlling 100 said semaphore, a plurality of bolts slidably mounted on said post attached to said trip-lever, wires attached to said bolts and extending longitudinally of the track to constitute a guard, and springs respectively in connection with said bolts and maintaining a 105 tension in said wires.

3. In apparatus of the class described, in combination, a post having a plurality of recesses therein, bolts slidably mounted in said 110 post and extending through said recesses, a plurality of wires attached to said bolts respectively, a trip-lever connected with said bolts and attached to said post, a signal carried by said post and controlled by said trip-lever, and springs disposed respectively in 115 said recesses and maintaining a tension in said wires.

In testimony whereof I have signed my name to this specification in the presence of 120 two subscribing witnesses.

GEORGE DILLEY WATSON.
